PLUG CONNECTER

William Huppert, New York, N. Y., assignor to
Ampex, Inc., New York, N. Y., a corporation of
New York

Application May 11, 1933, Serial No. 670,431

14 Claims. (Cl. 200—51)

This invention relates to plug connectors for electric flat irons and other electrical appliances.

An object of this invention is to provide a plug connector of the character described having a two part insulating housing and provided with novel means for detachably attaching the parts of the housing together without the use of screws, rivets, bolts or the like fastening devices.

A further object of this invention is to provide in a plug connector of the character described, a highly improved and novel switch which shall be positive in operation and insure a good electrical contact.

A still further object of this invention is to provide a plug connector of the character described having improved heat insulating means for obviating the danger of injury to the hands of the person manipulating the plug connector.

Still another object of this invention is to provide a compact, strong and rugged plug connector of the character described, which shall be relatively inexpensive to manufacture, comprise few and simple parts, easy to assemble and disassemble for repair, and which shall nevertheless be practical and efficient to a high degree.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an elevational, cross-sectional view of a plug connector embodying the invention;

Fig. 2 is an elevational interior view of the plug connector, with one of the housing parts removed;

Fig. 3 is an elevational interior view of the other housing part;

Fig. 4 is a cross-sectional view taken on line 4—4 of Fig. 2;

Fig. 5 is a fragmentary, cross-sectional view taken through the ball and cup of the switch;

Fig. 6 is a perspective view of the pin attaching device for the housing parts;

Fig. 7 is a cross-sectional view taken on line 7—7 of Fig. 1; and

Fig. 8 is a perspective view of my improved plug connector.

Referring now in detail to the drawing, 10 designates a plug connector embodying the invention,

comprising a pair of mating, hollow insulating housing parts or sections 11 and 12 made of phenol-condensate products or any other suitable material, having mutually contacting edges 11a and 12a. The housing parts 11 and 12 are substantially similar in outer shape and provided with lower end walls 14 and 14a respectively, each formed with a pair of spaced, curved notches 15. The notches 15 of the housing part 11 register with the notches 15 of the housing part 12 to form two openings 15a at the lower end of the housing for receiving plug blades or terminals of an electric heating iron or other electrical appliance.

The upper end walls 20 and 20a of the housing parts 11 and 12 respectively, are each formed with a semi-circular recess or notch 16, said notches registering to form a neck opening 17 for receiving a flexible tube 19 through which the duplex cable 18 passes into the plug tube 19. Said end walls 20, 20a are further formed with semi-circular grooves 21 registering to form an annular or circular groove for receiving the flange portion 22 of the flexible tube 19. The grooves 21 are formed with recesses 21a receiving projections 22a in said flange portion 22 to prevent rotation of said tube. Said tube 19 may be made of rubber and protects the duplex cable 18. It is formed at the end thereof with handle extensions 22b which may be grasped by the fingers 30 for disconnecting the plug from an electrical appliance to which the same may be attached. The edge of said upper end wall 20 of the housing part 11 is further formed on opposite sides of the neck opening with small projecting dowel pins 23, and the edge of the upper end wall 20a of the housing part 12 is formed with openings 24 receiving said pins 23 to aid in registering said housing parts when assembled.

The housing part 11 is formed with a bottom wall 27 and side walls 28 and 29 extending from the lower end wall 14 to the upper end wall 20. The lower end wall 14 is formed at the middle thereof and on the outer surface thereof with a recess or cavity 30 and with a groove 31 interconnecting said recess 30 with the inner flat surface of said lower end wall. Extending from the middle of the lower end wall 14 on the inside thereof, toward the upper end wall, is a projection 32 formed with a groove 32a communicating with the groove 31 and having a recess or notch 33 therein.

Projecting from said bottom wall 27 is a shallow boss 35 extending from the portion 32 and formed with a central cylindrical opening 36. There ex-

tends from said bottom wall 27 and adjacent the boss 35, a projection 37 extending above the plane of the edge 11a. Said projection 37 is formed with a slot or groove 38 extending to the outer surface 39 of said bottom wall. Extending from 5 said bottom wall is another post or projection 41 aligned with the projection 37, having the height thereof and formed with a slot or groove 42, likewise communicating with the outer surface 39 of 10 said bottom wall.

The housing part 12 is likewise formed with a bottom wall 27a, similar to the bottom wall 27 of the housing part 11. Extending from the bottom wall 27a are side walls 28a and 29a adapted 15 to register with the side walls 28 and 29 of the housing part 11. Extending from the lower end wall 14a of said housing part 11 is a projection 50 extending towards the upper end wall 20a formed with a groove 51 registering with the groove 32. 20 Extending from the bottom wall 27a is a post 53 formed with a slot 54 communicating with the outer surface 55 of said bottom wall 27a. The post 53 is adapted to be received between the projection 32 and the post 37 of the housing part 11 25 and is formed with a cylindrical lug 56 received within the opening 36 to aid in registering the housing parts.

Extending from the bottom wall 27a is a second post 59 substantially similar to the post 53 received between the posts 37 and 41 of the housing part 11. The post 59 is formed with a slot 60 communicating with the outer surface 55 of the bottom wall 27a of said housing part 12.

The slot 54, it will be noted, overlaps the slot 38 and the slot 60 overlaps the slots 38 and 42. The housing parts 11 and 12 may be placed together and fastened by means of an L-shaped pin 64, shown in detail in Fig. 6 of the drawing. Said pin 64 is provided with a shank 65 extending 35 through the overlapping portions of the slots 54, 38, 60 and 42. Extending from the shank 65 at an angle thereto, is a slightly curved portion 66 extending within the groove 31 and projecting into the recess 30. The portion 67 of shank 65 adjacent portion 66 is received within the registering grooves 32a and 51, said portion 67 being offset at 68 forming a hump adapted to snap into the recess 33 in the groove 32a to retain the pin from sliding out. The groove 51 is sufficiently deep to 40 permit the pin to be pushed back to disengage the hump 68 from recess 33 to allow withdrawal of 45 said pin.

As shown in Fig. 1 of the drawing, the inner edges 57 and 61 of the slots 54 and 60 are inclined 55 in one direction, whereas the inner edges 44 and 42a of the slots 38 and 42 respectively, are inclined in an opposite direction. With this construction, as the pin 64 is pushed through the slots 54, 38, 60 and 42 the end of the pin will be guided by 60 said inclined edges through the slots, and the pin will be slightly bent to effect a strong frictional grip. Thus as the forward end of the pin engages the inclined edge 57 as the pin is being introduced, said end of the pin will be guided onto the inclined edge 44. The inclined edge 44, will guide the end of the pin onto the inclined edge 61 from where said end will be guided onto the edge 42a. With this construction the two housing parts may be firmly attached together.

70 Of course, the housing parts may be separated by forceably withdrawing the pin 64, the recess 30 permitting a tool to be inserted beneath the end 66 of said pin for withdrawing the same.

It will now be understood that the shank 65 75 of the pin 64 may be seen through the openings

54 and 60 from one side of the plug connector and through the openings 38 and 42 from the other side of the plug connector.

Looking now at the housing part 11, there interconnects the post 41 with the side wall 29, a web portion 70 having a curved slot 71 and a shoulder 72 adjacent said curved slot. Extending from the bottom wall 27 are a pair of spaced posts 74, aligned with the notches 15, for the purpose hereinafter appearing. Adjacent the upper end wall 20 there extends from the bottom wall 27 a transverse wall 75, parallel to said end wall and having on one side thereof a curved slot 76, similar to the curved slot 71 in the web 70 and symmetrical therewith, and a shoulder 77 adjacent said slot 76. The edge of wall 75 is formed with a groove 78 adjacent one end thereof and a groove 79 adjacent the opposite end thereof. There further extends upwardly from said bottom wall 27 a boss 81 located substantially mid-way between the web 70 and the transverse wall 75 and adjacent the wall 28.

Fixed to the bosses 74 are a pair of folded over spring contact members 83 preferably each formed of a single piece of metal folded in half 25 and shaped for receiving the terminal blades or prongs inserted through the openings 15a at the lower end of the connector plug. The spring contacts 83 may be fixed to the posts or bosses 74 by means of screws or rivets 84, 84a or in any other suitable manner.

Screwed to the upper right hand corner of the housing part 11 between the wall 75 and the upper end wall 20 and adjacent the groove 78, is a terminal binding screw 86. Interconnecting the rivet 84a with the screw 86 is a strip of conducting metal 87, one end of which is fastened to the spring contact 83 by means of the rivet or screw 84a, and the other end of which is formed with a screw threaded opening receiving the screw 86. The strip 87 is preferably channel-shaped so as to be received within the housing part 12 when the parts are assembled. One of the wires from the duplex cable 18 may be fastened to the screw 86.

45 Mounted on the housing part 11 is a curved segmental track 90 preferably made of metal and having the ends thereof received within the slots 71 and 76. The track 90 is provided with guide flanges 91 on both sides thereof. Pivoted to the post 81 by means of a pin or rivet 93 fixed to said post, is a lever 95, preferably made of insulating material and projecting through a slot 96 formed in the wall 28. Attached to the inner end 99 of the lever 95 is a coil compression spring 100 engaging at the outer end thereof a ball 101 received within a cup-shaped member 102 formed with a central opening 103 permitting said ball to contact the inner surface of the curved track 90. As shown in Fig. 2 of the drawing, the spring 100 60 65 presses the ball upwardly for retaining the cup-shaped member 102 in contact with the shoulder 72. Should the lever 95 be depressed, when the end 99 thereof passes dead center, the spring 100 will force or snap the ball and cup 65 downwardly against the shoulder 72, the ball 101 having rolling contact with the track, during this action.

It will be noted that the opening 103 in the cup-shaped member 102 is of sufficient size to 70 permit a portion of the ball 101 to project therethrough for contacting the inner surface of the track 90. As the switch is actuated to the "on" and "off" position the ball 101 rolls on the inner surface of the track thereby reducing the friction 75

and wear of the parts to a minimum. The cup is somewhat loose and therefore does not frictionally rub against either the track or the projections 126, 120a. The cup prevents the ball 5 from slipping out during movement of the switch from the "on" to "off" position. By reason of the metal to metal contact between the ball and the track the fitting may be used for long periods of time without appreciable wear.

10 Attached to the rivet 84 and lying against the inner surface of the bottom wall 27 is a conductor strip 105 terminating in an ear at 106, adjacent the shoulder 77. As shown in Fig. 2 of the drawing, when the cup is in its upward position 15 or "on", the cup 102 is in contact with the ear 106. If desired, the ball may be omitted, the spring then acting directly on the cup 102.

Fixed to the wall 109, forming the bottom of the groove 79, is a rivet or screw 110, and fixed to said 20 wall by means of said screw or rivet is a conducting strip 112 having a portion in a plane substantially parallel to the plane of the conductor strip 105 and terminating in an ear 113 aligned with the ear 106 and parallel thereto and likewise 25 adapted to be engaged by the cup 102 when the latter is in the upper or "on" position. Screwed to the upper end of the conductor strip 112 is a terminal binding screw 115 to which there may be attached the other wire from the duplex cable 30 18. It will now be understood that in the position shown in Fig. 2 the switch is "on" the current passing from one of the conductor wires through the conductor strip 87 to one spring contact member 83, and from the other wire 35 through the conductor strip 112, cup 102, and conductor strip 105, to the other spring contact member 83.

When the outer end or handle portion of the lever 95 is depressed, the spring pressed cup 40 moves to the lower portion thereof and the switch is "off". There extends upwardly from the bottom wall 27 of the housing part 11 a curved wall 120 adapted to contact one side of the cup 102 when the latter is moved to its downward position.

45 The wall 28a of the housing part 12 is formed with a slot portion 96a registering with the slot portion 96 of the wall 28 of the housing part 11, said slots together forming an opening for the lever 95. Extending from the wall 27a of said housing part 12 is a wall or web 75a adapted to register and have edge to edge contact with the wall 75. The walls 75, and 75a together form a partition adjacent the upper end of the plug connector, acting as a heat insulator and protector adjacent the neck opening of the plug connector.

Extending from the bottom wall 27a of the housing part 11 is a curved wall 120a aligned with the curved wall 120 of the housing part 11 and 60 adapted to engage the side flanges of the cup 102 when the latter moves to its downward position, said cup thus being received between said curved walls 120 and 120a which aid in guiding the movement of the said cup.

65 Extending from the transverse wall 75a of the housing part 12 is a stepped portion 130 adapted to contact one side edge of the upper end of the curved track 90. Extending from the bottom wall 27a of said housing part 12 is a small post 70 131 adapted to engage the side edge of the lower end of said track 90. With this construction, the track is firmly held in place when the housing parts are attached together.

Extending from the walls 29 and 29a of the 75 housing parts 11 and 12 are webs 121 and 121a

adapted to be aligned with and engage the outer surface of the track 90 to aid in positioning said track. A cylindrical projection 123 extending from the bottom wall 27a of the housing part 12 serves to receive a portion of the screw or rivet 5 93 when the housing parts are placed together.

It will now be understood that all of the metal or current carrying parts may be attached and assembled with the housing part 11. The wires from the conductor cable 18 may be attached to 10 the binding posts and thereafter the housing part 12 may be placed over the housing part 11 and the pin 64 inserted to attach the two parts together.

The housing parts 11 and 12 are preferably 15 molded. In molding said members the bottom of the molds may be provided with projections for forming the slots 42 and 38 of the member 11 and the slots 54 and 60 of the housing member 12. By molding the members in this manner the 20 molded members can be readily removed from the molds by merely lifting.

It will thus be seen that there is provided a device in which the several objects of this invention are achieved, and which is well adapted to 25 meet the conditions of practical use.

As various possible embodiments might be made of the above invention, and as various changes might be made in the embodiment above set forth, it is to be understood that all matter 30 herein set forth or shown in the accompanying drawing is to be interpreted as illustrative and not in a limiting sense.

Having thus described my invention, I claim as new and desire to secure by Letters Patent:— 35

1. An electrical attachment fitting comprising an insulating housing, a curved segmental track mounted within said housing, a lever pivoted to said housing, a coil compression spring attached to one end of said lever, a member slidably 40 mounted on said track having an opening, a ball received in said member and partially extending through said opening, said spring engaging said ball to press the same against the inner surface of said track.

2. An electrical attachment fitting comprising an insulating housing, a curved segmental track mounted within said housing, a lever pivoted to said housing, a coil compression spring attached to one end of said lever, a member slidably 50 mounted on said track, having an opening, a ball received in said member and partially extending through said opening, said spring engaging said ball to press the same against the inner surface of said track, said track having flanges engaging 55 opposite sides of said member for guiding the same.

3. An electrical attachment fitting comprising an insulating housing having a pair of spaced walls formed with slots, a curved track mounted 60 within said housing and having the ends thereof received within said slots, a lever pivoted to said housing, a spring attached at one end thereof directly to an end of said lever, and a member directly engaging the inner surface of said track 65 and pressed by said spring against said inner surface, and means actuated by said spring for slidably moving said member in said track.

4. An electrical attachment fitting comprising an insulating housing having a pair of spaced 70 walls formed with slots, a curved track mounted within said housing and having the ends thereof received within said slots, a lever pivoted to said housing, a spring attached at one end thereof directly to an end of said lever, and a member di- 75

- rectly engaging the inner surface of said track and pressed by said spring against said inner surface, said track having guide flanges engaging opposite sides of said member.
5. An electric attachment fitting comprising an insulating housing having a pair of spaced walls formed with slots and shoulders adjacent said slots, a curved track having the ends thereof received within said slots, a lever pivoted to said housing, a spring attached at one end thereof to an end of said lever, a cup-shaped member engaging the inner surface of said track, said cup-shaped member having an opening, a ball pressed by said spring against the inner surface of said track, said ball extending through said opening in said cup-shaped member, said cup-shaped member being adapted to strike said shoulders upon manipulating said lever.
6. An electric attachment fitting comprising an insulating housing having a pair of spaced walls formed with slots and shoulders adjacent said slots, a curved track having the ends thereof received within said slots, a lever pivoted to said housing, a spring attached at one end thereof to an end of said lever, a cup-shaped member engaging the inner surface of said track, said cup-shaped member having an opening, a ball pressed by said spring against the inner surface of said track, said ball extending through said opening in said cup-shaped member, said cup-shaped member being adapted to strike said shoulders upon manipulating said lever, and said curved track having a pair of flanges engaging opposite sides of said cup-shaped member.
35. 7. An electric attachment fitting comprising an insulating housing, a curved track within said housing, a lever pivoted to said housing, a ball engaging the inner surface of said track, and a spring cooperating with said lever for directly pressing said ball against said track, a member slidably movable in said track and adapted to be so moved by said ball.
8. An electrical attachment fitting comprising an insulating housing, a curved segmental track mounted within said housing, a lever pivoted to said housing, a coil compression spring attached to one end of said lever, a member slidably mounted on said track and having an opening, a ball received in said member and partially extending through said opening, said spring engaging said ball to press the same against the inner surface of said track, and means on opposite sides of said member for guiding the same during movement thereof.
50. 9. An electrical attachment fitting comprising an insulating housing, a curved segmental track mounted within said housing, a lever pivoted to said housing, a coil compression spring attached directly to one end of said lever, a member slidably movable on said track, said spring engaging said member to press the same directly against the inner surface of said track.
10. An electrical attachment fitting comprising an insulating housing and a switch within said housing including a curved track, and a member having rolling contact with said track, said member being freely rotatable in all directions, and means for oscillating said member on said track.
11. An electrical attachment fitting comprising an insulating housing, a curved metal track within said housing, a lever pivoted to said housing, and a spring pressed metal member frictionally engaging the inner surface of said track and means cooperating with said lever for slidably moving said member along the surface of said track.
12. An electrical attachment fitting comprising an insulating housing, a curved metal track within said housing, a lever pivoted to said housing and a spring pressed metal member directly engaging the inner surface of said track and cooperating with said lever, said spring pressed member having universal rolling contact with said track, said track being provided with guide flanges engaging opposite sides of said member.
13. An electrical attachment fitting comprising a pair of mating housing insulating parts, means for attaching said parts together, a curved track within said housing, a shaft fixed to one of the housing parts, a lever pivotally mounted on said shaft, a spring attached at one end thereof to said lever, a member engaging said spring and pressed thereby against the inner surface of said track, said other housing part having a tubular portion receiving the free end of said shaft.
14. An electrical attachment fitting comprising a pair of mating housing parts, one of said parts being formed with spaced slots, an independent curved track member mounted within said housing parts and having the ends thereof received within said slots, a lever pivoted to said housing, a spring attached at one end thereof to an end of said lever, a member engaging the inner surface of said track and pressed by said spring against said inner surface, and projections on the other of said housing parts engaging the side edges of the ends of said curved track to aid in positioning of said track.

WILLIAM HUPPERT. 55
